(57) **CLAIM**

The ornamental design for a lug nut, as shown and described.

DESCRIPTION

FIG. 1 is a perspective view of a lug nut of the present invention;

FIG. 2 is a top plan view of the lug nut of FIG. 1, which is a mirror image of the bottom plan view;

FIG. 3 is a left side elevation view of a lug nut of FIG. 1, which is a mirror image of the right side elevation;

FIG. 4 is an enlarged end view of the lug nut of FIG. 3; and, FIG. 5 is the other end view of the lug nut of FIG. 3.

The broken lines are included for illustrative purposes only and form no part of the claimed design.
